UNITED STATES PATENT OFFICE.

STEFANUS NIELSEN, OF NEW YORK, N. Y., ASSIGNOR TO UNION TYPEWRITER COMPANY, OF ILION, NEW YORK, A CORPORATION OF NEW YORK.

TYPE-WRITING MACHINE.

964,878.

Specification of Letters Patent. Patented July 19, 1910.

Application filed April 29, 1910. Serial No. 558,439.

To all whom it may concern:

Be it known that I, STEFANUS NIELSEN, a citizen of the United States, and resident of Westchester, city of New York, in the county of New York and State of New York, have invented certain new and useful Improvements in Type-Writing Machines, of which the following is a specification.

My invention relates especially to ribbon mechanism for typewriting machines.

The general object of the invention is to provide improved mechanism of the class referred to.

More specifically one object of the invention is to provide means for enabling the ribbon to be used substantially throughout its entire width in that class of machines where the ribbon is vibrated at printing operation, and particularly as shown in the present instance in machines which employ a shiftable platen.

Another object of my invention is to provide for dispensing at will with the automatic cross feeding or variation in the throw of the ribbon and to provide instead for throwing the vibrating ribbon predetermined extents in order to make use at pleasure of different ribbon fields and particularly in machines which employ a shiftable platen.

Other objects will hereinafter appear.

To the above ends my invention consists in the features of construction, combinations of devices and arrangements of parts hereinafter described and particularly pointed out in the claims.

My invention may be carried out in various ways, one of which is shown in the accompanying drawings, wherein—

Figure 1 is a vertical front to rear sectional view of so much of a front-strike typewriting machine as is necessary to a clear understanding of my invention. Fig. 2 is a front elevation partly in section of said machine. Fig. 3 is a perspective view of certain of the ribbon controlling devices to which my invention more especially relates, said devices including a shiftable frame. Fig. 4 is a plan view of said shiftable frame and of an eccentric which is adapted to control the same. Fig. 5 is a view partly in section of said eccentric and its support. Figs. 6 and 7 are vertical sectional views showing in different relation-

ships the ribbon controlling devices of Fig. 5 and associate parts. Figs. 8, 9 and 10 are operating views showing in side elevation and partly in vertical section, the ribbon vibrating mechanism and associate parts, the mechanism appearing in different relationships in the various views. Fig. 11 is a side elevation of certain hand actuated devices for setting the ribbon controlling devices. Fig. 12 is a diagrammatic plan view of the mechanism for feeding the ribbon longitudinally.

In various of the views parts are omitted and parts broken away.

My invention is shown adapted to a machine which is substantially like the No. 10 Remington typewriter but it is to be understood that said invention may be applied to other styles of writing machines.

In carrying out my invention I provide a ribbon vibrator or carrier which occupies a single normal position and which is thrown different extents to bring different widthwise portions of ribbons into use, the extent of throw being increased when the platen is shifted, in order to compensate for the changed position of the printing point.

As appears in Figs. 1 and 2 of the drawings the main frame of the machine comprises a base 1, corner posts 2 and a top plate 3. Said top plate supports fixed grooved trackways 4 which provide bearings for anti-friction balls 5, said balls also cooperating with grooved front and rear bars 6 and 7 of a carriage which further comprises end bars 8, said end bars being connected by links 9 with a shiftable platen frame or carrier 10 which supports a cylindrical platen 11. A roller 12 is mounted on the platen carrier below the platen and cooperates with a shiftable guide rail 13, which is part of a shift frame comprising vertical side bars 14 and a cross rod 15. The lower ends of the bars 14 are each pivotally connected to a shift lever 16 mounted on a rock shaft 17 and provided with a key 18 depressible to operate the platen shifting means and so raise the platen carrier and platen to upper case position, the shifting movement being independent of the carriage proper.

Key levers 19 are pivotally mounted in the rear of the base 1 and are connected with type bars (not shown) which are adapted

to coöperate with the front face of the platen 11. A universal bar 20 underlies the key levers and is connected by links 21 with crank arms 22 fixed to a rock shaft 23 near the ends thereof, said rock shaft having fixed bearings at the sides of the base 1. The carriage is connected by a band or strap (not shown) with a spring drum 24 (Fig. 12), which impels the carriage step-by-step during the printing of the lines of writing, the step-by-step movement being controlled by escapement devices (not shown) which are connected with the rock shaft 23 and operated when the universal bar 20 is actuated by the key levers 19.

A ribbon 25 is wound on vertical ribbon spools 26 one arranged at each side of the machine below the top plate, each ribbon spool being secured at the forward end of a horizontal rearwardly extending shaft 27. In order not to confuse unduly the main sheets of drawing, the means for feeding the ribbon longitudinally is separately illustrated in the diagrammatic plan view (Fig. 12). As shown in this figure, each shaft 27 has secured to its rear end a beveled pinion 28 which is adapted to mesh with a beveled pinion 29 secured to a driving shaft 30 connected by beveled pinions 31 and 32 with the spring drum 24 in such a way that the shaft is turned by the spring drum as the latter moves to advance the carriage in printing direction. The shaft 30 is movable endwise independently of the pinion 31 which has a sliding connection therewith, the endwise movement of the shaft being preferably effected automatically and operating to connect the pinions 29 alternately with their associate pinions 28 so that the ribbon may be fed alternately back and forth from one ribbon spool 26 to the other.

Midway between the ribbon spools the ribbon is threaded through an upright vibratory ribbon carrier or vibrator 33 which is supported and guided on a guide 34 fixed to the frame of the machine. The lower end of the vibrator carries a cross pin 35 which is engaged by the slotted forward end of an operating lever 36 pivoted at 36^a to a bracket 36^b fixed to the top plate. The rear arm of the lever 36 is formed with an arcuate slot 37 which is engaged by a pin 38 extending laterally from the top of a vertically disposed link 39, the lower end of said link being pivotally connected with the horizontal arm of a bell crank lever 40 pivoted at 41 to a bracket 42 screwed to the top of the base 1 at the rear thereof. The downwardly extending arm of the bell crank 40 is pivotally connected by a horizontally disposed and forwardly extending link 43 with a crank arm 44 fixed to and rising from the rock shaft 23. A coiled spring 45 connects the link 39 with a pin 46 fixed to the bracket 42, said spring constantly urging the link 39

rearward and tending to maintain the pin 38 at the rear of the slot 37. The construction is such that a depression of one of the key levers 19 will act on the universal bar 20 to rock the shaft 23 rearward, causing the link 43 to act through the bell crank 40 on the link 39 to pull said link 39 downward, thereby actuating the lever 36 and causing the forward arm of the latter to rise and lift or throw the vibrator 33 upward so as to bring opposite the printing point on the platen the printing portion of the ribbon or that portion which is between the bifurcations or arms 33^a comprised in the head of the vibrator.

Obviously the extent of throw of the vibrator may be varied by varying the relationship between certain of the vibrator actuating devices aforesaid. In the present case the point of operative engagement between the pin 38 and the slotted lever 36 is varied, thus changing the widthwise portion of the ribbon presented to the types. Means are provided for automatically and progressively moving the link 39 and causing the pin 38 to move step-by-step toward and away from the pivot 36^a, with the result that the throw of the vibrator is automatically varied so as to change progressively the widthwise portion of the ribbon presented to the types. When automatic means of this character are employed, it is commonly in connection with a ribbon of uniform character, and not a ribbon of dual character like the ribbon 25 shown herein. Said automatic means comprises in the present instance eccentric devices which are connected with and operated by the ribbon driving shaft 30, said devices communicating a reciprocatory movement to a cam member 105 which operates during movement in one direction to swing the link 39 forward and which, during its return movement, permits the spring 45 to swing the link 39 rearward (see Figs. 1 to 5). Said eccentric devices 110 comprise an eccentric member 47 having an eccentric working face 48 and at its lower end a concentric neck 49. The eccentric member is slidably mounted on a vertical shaft 50 but is forced to turn with said shaft, 115 the connection between the two, comprising a spline 51 fast on the eccentric and which engages a longitudinal groove 52 in the shaft 50. Said shaft is supported on an angular bracket 53 depending from the under side of the top plate and is held from dropping out of said bracket by the hub 54 of a beveled pinion 55 which is secured to the upper end of the shaft 50 above the horizontal arm of the bracket 53. Said beveled pinion 125 meshes with a beveled pinion 56 fixed to the driving shaft 30, which shaft passes through an opening in the vertical arm of the bracket 50. The beveled pinion 56 is provided with a hub 57 which is splined to the shaft 30, 130

the construction permitting endwise movement of the shaft independent of the pinion. Rotary movements are communicated from the shaft through the pinions 56 and 55 to 5 the shaft 50 and the eccentric member. A leaf spring 58 secured to the bracket 53 acts against the eccentric member, tending constantly to press it downward and to maintain the lower end of the spline 51 in 10 contact with a limiting pin 59 at the lower end of the shaft 50 (Fig. 5).

When the eccentric member is in its lowest position the eccentric face 48 co-operates with opposite interior faces of a rectangular opening 60 formed in the head 61 of a reciprocating frame 62, said frame further comprising a pair of depending ears 63 formed with bearing openings which engage with a short supporting rod 64. Said rod is 20 secured at its ends by a pin 65 to the parallel ears 66 of a stationary bracket 67 which further comprises a cross bar 66^a connecting the ears 66 and also an upright extension 68 on the left-hand ear, said extension being secured to the under side of the top plate 3. Bearing on the rod 64 and confined between the ears 63 is a sleeve 69 which is part of a cam member 70, said cam member further comprising an arm 71 inclining downward 25 and forward from the sleeve and having at its lower end a laterally disposed cam proper 72. The cam 72 inclines upward and leftward from its point of connection with the arm 70 and terminates in a horizontally disposed portion 73. A vertically disposed ear 74 extends forward from the left end of the portion 73 and is provided with a lateral pin 75, which pin engages in a slot 76 at the rear end of an arm 77, said arm curving downward and rearward from the cross rod 15 and being provided with a hub 78 which is secured to said cross rod so that the arm 77 will shift with the platen shifting frame and will act through the pin and slot connection 75, 76 on the cam member 70, causing said cam member to turn on the rod 64 as a center. The forward edge 72^a of the cam 72 inclines forward from right to left or fore and aft of the machine and is adapted to co-act directly with the link 39.

During the printing movements of the carriage the driving shaft 30 will turn and communicate rotary movements to the eccentric member, causing the eccentric face 48 to co-act with the left-hand and right-hand inner faces of the opening 60 so as to move the frame 62 progressively along the rod 64 first in one direction and then oppositely, the extent of back and forth movement corresponding with the throw of the eccentric 48, as will be understood from a consideration of the full and dotted line positions of the head 61 and eccentric 48 shown in Fig. 4. The front and rear inner faces of the opening 60 are far enough apart

so as not to interfere with the turning movements of the eccentric 48. When the eccentric 48 and the frame 62 are in the positions shown in Fig. 2 and by full lines in Fig. 4, the link 39 will be in contact with the front edge of the arm 71 as shown in Figs. 1 and 2, this contact being maintained by the spring 45. As a result the pin 38 will operate at the rear end of the slot 37 and will throw the vibrator upward to present the upper edge portion of the ribbon to the types at printing operation. During subsequent printing operations the eccentric 48 will operate on the frame 62 to slide the same rightward along the rod 64 until the dotted line position indicated in Fig. 4 is reached, after which the return movement of the frame will take place. As the frame 62 slides rightward it operates to slide the sleeve 69 rightward along the rod 64, thereby causing a rightward movement of the entire cam member 70, the cam edge 72^a acting against the link 39, swinging the same forward against the pull of the spring 45 and moving the pin 38 forward in the slot 37. When the rightward limit of movement of the cam member is reached, the forward edge 72^a of the portion 73 will be in engagement with the link 39 and the pin 38 will be in the position shown in Fig. 9. The result of the progressive movement of the pin 38 will be that the throw of the operating lever and ribbon vibrator will gradually increase and the points at which the type impressions occur on the ribbon will gradually approach the bottom edge thereof. During the return movement of the cam member the link 39 will be swung back by the spring 42 as the cam edge 72^a moves leftward, and consequently the pin 38 will again approach the rear end of the slot 37. During the change of the ribbon widthwise it is also being fed lengthwise from spool to spool so that the result will be that the type impressions will follow a serpentine course lengthwise of the ribbon from one edge to the other.

During the back and forth movements of the cam member the pin 75 will move to and fro transversely of the slot 76 without disturbing the arm 77; but so that the connection between the pin and slot will be always effective to cause the cam member to swing upward whenever the platen is shifted to upper case position. The effect of this upward swing of the cam member will be discussed after the operation of the mechanism for two-color work, or similar work, has been explained.

When a ribbon like 25, which is divided longitudinally so as to provide two fields or stripes *a* and *b* of different characteristics, such as different colors, is to be employed, the automatic mechanism comprising the eccentric 48 is preferably thrown out of operation and the link 39 is set by hand in either

one of a plurality of predetermined positions so that the vibrator may be thrown predetermined extents at pleasure in order to present either of the fields *a* and *b* to the types. The means for carrying out these operations comprise a shift frame 79 which is clearly shown in Fig. 3 and also appears in Figs. 1, 2, 6 and 7. The frame 79 is U-shaped, having opposite parallel arms 80 connected at one end by a cross piece 81. The arms 80 pass through pairs of narrow parallel vertical slots 63^a in the frame ears 63. Said arms 80 are supported by the bracket 67, engaging in parallel guide slots 82 formed in the ears 66 of said bracket 67. The arms 80 are movable back and forth in said guide slots transversely of said ears when the shift frame 79 is reciprocated by hand. The frame 62 and the shift frame 79 are movable together and also relatively to each other as hereinafter more fully explained. Pairs of pins 83 and 84 on said arms 80 are adapted to contact with the outer faces of the ears 63 to move the frame 62 and also limit the extent of back and forth movements of the frame 79. The guide slots 82 are wider than the slots 63^a and the pins 83 pass freely through the slots 82 but not through the narrower slots 63^a. The arms 80 are cut away or notched as indicated at 85, the sides 86 and 87 of each notch being oppositely inclined and the bottom 88 of each notch being horizontal. Suitable connections conveniently controlled from the front of the machine are provided for shifting the frame 79. Such connections are shown in Figs. 2 and 11 and comprise a rod 89 adjustably secured to the cross piece 81, said rod extending rightward and being provided with a pin 90 engaging a slot 91 in an upright crank arm 92 fixed to a rock shaft 93. Said rock shaft has a bearing 94 fixed to the base 1 at the right-hand side thereof and extends forward through the right-hand front corner post 2, taking a bearing therein. An upwardly extending arm 95 is fixed to the rock shaft forward of the corner post, said arm terminating in a pointer 95^a and being provided with a finger piece 96 at the front and with a pointed lug 97 at the rear. The lug 97 cooperates with holes 98, 99 and 100 in the corner post to hold the arm 95 and connected parts in set positions. Suitable indicating marks may be provided contiguous to the holes for coöperation with the pointer 95^a. The arm 95 is sufficiently flexible to permit the disengagement of the lug 97 from one of the holes and its reengagement with another of the holes when the finger piece 96 is operated to rock the shaft 93. Stop pins 101 on the corner post coöperate with the arm 95 to limit the extent of rocking movement. When the shaft is rocked its movement is transmitted from the arm 92 to the

rod 89 and shift frame 79 so that said shift frame may be slid from the Fig. 2 position to the Fig. 6 or Fig. 7 positions.

Suppose that it is desired to throw out the automatic cross feed and to print lengthwise of the upper field *a* of the ribbon: then the finger piece 96 is pushed leftward until the lug 97, after disengaging from the central hole 98, engages with the hole 99. This movement is communicated to the shift frame 79 and causes the inclined edges 86 to act against the neck 49 of the eccentric member, exerting a camming action against the latter and sliding it upward on the shaft 50, at the same time compressing the spring 58. The upward movement of the eccentric member continues until the tops of the inclined edges 86 are reached, after which the top surfaces of the arms 80 will slide along under the neck 49 and will hold the eccentric member up out of engagement in the Fig. 6 position. During this latter part of the movement the ears 83 may contact with the right-hand ear 63 and will force the frame 62 leftward, the frame carrying with it the cam member 70. The movements of the parts will be limited by the engagement of the frame 62 with the left-hand ear 66 as shown in Fig. 6. At this time the link 39 will be engaged with the front edge of the arm 71 so that during subsequent actuation of the printing keys the vibrator will receive its least extent of throw from normal position and the ribbon field *a* will be presented to the types, the type impressions following a straight course longitudinal of the upper field *a*.

If it should be desired to print longitudinally of the lower ribbon field *b* the finger piece 96 is pushed rightward to the limit of its movement, causing the pin 97 to engage with the hole 100 and sliding the frame 79 from the Fig. 6 to the Fig. 7 position. During this movement of the slide frame the eccentric member, after sliding down the edges 86, will be cammed up to the top edges of the arms 80 by the inclined edges 87 and the frame 62 will be slid rightward by the pins 84 carrying with it the cam member 70 until the link 39 engages with the forward edge of the portion 73 of said cam member as shown in Fig. 7. This sets the link 39 forward in the Fig. 9 position and causes it, when pulled down, to lift the vibrator to present the lower ribbon fields *b* to the types. The eccentric member may be restored to operation so as to again provide for cross feeding the ribbon by resetting the arm 95 and the parts controlled thereby in the Fig. 2 position.

As has been stated, the pin and slot connection 75, 76 is always effective to swing the cam member 70 upward on the rod 64 as a center whenever the platen is shifted to upper case position, and vice versa. It will

be apparent that when the cam member is thus swung upward the link 39 will be swung forward and the pin 38 will be reset at a new position in the slot 37 but without affecting the operating lever or the vibrator, which have the same normal position for both positions of the platen. The purpose of this resetting movement is, of course, to increase the throw of the vibrator to compensate for the shifting of the platen, so that the types may print on the same width-wise portion of the ribbon in the upper case position of the platen as when the platen is in the lower case position. The extents of this compensatory increase in throw must vary according to the lower case position occupied by the pin 38 in the slot 37 at the time the platen shift occurs. If the compensatory change or shift of the pin 38 were always the same in extent the compensatory change or throw of the vibrator and ribbon would not be uniform but would vary as a result. In order to provide for the proper extent of compensatory shift in whatever position the link 39 may happen to be, I have resorted to the expedient of inclining the cam proper 72 in a direction from top to bottom of the machine as described. Consequently as the point of contact of the link 39 with the cam member approaches the higher part of the latter, the result of extent of shift movement of the link when the platen is shifted will be less than when the link just prior to the platen shift is engaged with a lower part of the cam 72. In other words, when the pin 38 is farthest from the fulcrum of the operating lever said pin will receive its greatest compensatory shift and as said pin moves forward toward the fulcrum of the operating lever its extent of compensatory shift will gradually lessen until the pin reaches its extreme forward position for lower case, at which time the compensatory shift communicated to said pin will be at a minimum. These statements will perhaps be clearer from a consideration of an example or two. Suppose first that at the time the platen shift occurs the parts are in the relationship shown in Fig. 1 with the cam member at the lowest point of its downward swing and the link 39 in its rear-most position with the pin 38 at the rear of the slot 37. Then when the platen is shifted the arm 77 will move upward and will swing the cam member forward and upward on its pivot, thus forcing the link 39 forward and shifting the actuating pin 38 to a new position in the slot 37. The parts will now be in the position shown in Fig. 8. Comparing Figs. 1 and 8 it will be observed that the compensatory shift has carried the pin 38 well toward the front end of the slot 37, this comparatively great extent of movement of the pin being due to the fact that the forward edge of the arm 71 with which the link

39 is in contact in swinging upward to its new position will also move forward a considerable extent at the same time. On the other hand, comparing Figs. 9 and 10, which may be considered as representing respectively the lower case and upper case positions of the parts when the pin 38 is nearest the fulcrum of the operating lever, it will be seen that the compensatory shift of the pin is much less, owing to the fact that although the forward edge of the part 73 which is in control of the link 39 has the same extent of angular movement as the arm 71, yet, nevertheless, said part 73 has a much less movement forward during its upward swing, owing to the fact that it is nearer the horizontal and moves upward much more rapidly than it moves forward. On the other hand, in the case of the arm 71 its forward movement is almost as rapid as its upward movement.

It will be seen that I provide a simple and efficient construction for enabling a vibratory ribbon to be shifted from a single normal position to compensate for the platen shift; that the ribbon may be variably thrown for cross-feeding; that the cross-feeding may be dispensed with and the parts set to throw the ribbon different predetermined extents; and that the compensating shift does not interfere with the proper operation of the variable throwing means or the predetermined movements of the ribbon.

Various changes may be made without departing from the scope of my invention.

What I claim as new and desire to secure by Letters Patent, is:—

1. In a typewriting machine, the combination of a platen, shifting means therefor, a ribbon vibrator, means for vibrating the same including a link, a cam operative on said link to vary the action of the vibrating means, and connections between said cam and said shifting means.
2. In a typewriting machine, the combination of a platen, a key operated frame for shifting the same, a ribbon vibrator, means for vibrating said vibrator including a link, a cam operative on said link to vary the action of the vibrating means, and an arm on said frame having a pin and slot connection with said cam.
3. In a typewriting machine, the combination of a platen, shifting mechanism therefor, a ribbon vibrator, means for vibrating the same including a link, a cam operative on said link to vary the action of the vibrating means, and connections between said cam and said shifting means, said cam being movable independently of said shifting means to vary the action of the vibrating means.
4. In a typewriting machine, the combination of a platen, shifting means therefor, a ribbon vibrator, actuating means for said

vibrator, a slidable cam operative to vary the action of said actuating means, an arm on said shifting means provided with a lateral pin, and a connection to said cam having a slot engaged by said pin.

5. In a typewriting machine, the combination of a platen, shifting means therefor, ribbon vibrating devices, means for varying the action of said vibrating devices including a slidable member, and means connected with said shifting means for swinging said member pivotally.

6. In a typewriting machine, the combination of a platen, shifting means therefor, a ribbon vibrator, actuating devices for the same, ribbon feeding means, a member operative on certain of said devices to vary the action thereof, means connected with said ribbon feeding means for moving said member slidably, and means connected with said shifting means for swinging said member pivotally.

7. In a typewriting machine, the combination of a platen, shifting means therefor, ribbon vibrating devices including a link, ribbon feeding means, a cam slidable by said feeding means and operative to shift said link, and connections between said shifting means and said cam for pivotally turning said cam.

8. In a typewriting machine, the combination of a platen, shifting means therefor, ribbon vibrating devices, ribbon feeding means, a cam member co-operative with certain of said vibrating devices, connections between said cam member and said shifting means, and connections between said cam member and said ribbon feeding means, both said connections actuating said cam member to operate on said devices.

9. In a typewriting machine, the combination of a platen, a ribbon vibrator, actuating devices therefor including a lever and a link, automatic means including a cam for varying the relationship between said lever and said link, and connections between said cam and said platen shifting means.

10. In a typewriting machine, the combination of a platen, platen shifting means, a slotted operating lever, a key controlled actuating link engaging the slot in said lever, an automatic cam operative on said link to change its position, and connections between said cam and said platen shifting means.

11. In a front-strike typewriting machine, the combination of a platen, platen shifting means, an upright ribbon vibrator, a horizontally disposed operating lever provided with a slot, a vertically disposed actuating link engaging said slot, key controlled devices with which the lower end of said link is pivotally connected, automatic means for swinging said link on its lower end as a pivot, and connections between said automatic means and said platen shifting means

by which said link is swung pivotally when the platen is shifted.

12. In a front-strike typewriting machine, the combination of a platen, platen shifting means, an upright ribbon vibrator, a horizontally disposed operating lever provided with a slot, a vertically disposed actuating link engaging said slot, key controlled devices with which the lower end of said link is pivotally connected, automatic means for swinging said link on its lower end as a pivot, and connections between said automatic means and said platen shifting means by which said link is swung pivotally when the platen is shifted, said automatic means comprising a cam that is movable slidably and also pivotally.

13. In a front-strike typewriting machine, the combination of a platen, platen shifting means, an upright ribbon vibrator, a horizontally disposed operating lever provided with a slot, a vertically disposed actuating link engaging said slot, key controlled devices with which the lower end of said link is pivotally connected, automatic means for swinging said link on its lower end as a pivot, and connections between said automatic means and said platen shifting means by which said link is swung pivotally when the platen is shifted, cams having an edge inclining in a direction fore and aft of the machine, said edge having also an inclination from top to bottom of the machine.

14. In a typewriting machine, the combination of a platen, a ribbon vibrator, an operating lever, a bell crank lever, a link connecting said operating lever and said bell crank lever, a second bell crank lever, a second link connecting the two bell crank levers, key levers, a universal bar operative by said key levers, and connections between said universal bar and said second bell crank lever.

15. In a typewriting machine, the combination of a platen, platen shifting means, a ribbon vibrator, actuating devices therefor, automatic means including a cam operating directly on certain of said actuating devices for varying the action of said actuating devices, and connections between said automatic means and said platen shifting means.

16. In a typewriting machine, the combination of a platen, a ribbon vibrator, actuating devices therefor including a lever and a link, a cam operative directly on said link to change its relationship with said lever, and connections between said cam and said platen shifting means.

17. In a typewriting machine, the combination of a platen, a ribbon vibrator, actuating devices therefor including a lever and a link, a cam operative either automatically or by hand at will and acting directly on said link to change its relationship with said lever, and means connected with said platen

- shifting means from moving said cam and shifting said link when the platen is shifted.
18. In a typewriting machine, the combination of a platen, platen shifting means, a ribbon vibrator having a single normal position, actuating devices therefor, and means for varying the relationship of said actuating devices independently of said platen shifting means, said platen shifting means, when actuated, operating said means.
19. In a typewriting machine, the combination of a platen, platen shifting means, a ribbon vibrator having a single normal position, actuating devices therefor, a member for changing the relationship between certain of said actuating devices, means for actuating said member independently of said platen shifting means, and connections between said member and said platen shifting means for actuating said member when the platen is shifted.
20. In a typewriting machine, the combination of a platen, platen shifting means, a ribbon vibrator having a single normal position, variable actuating devices for said vibrator, and means connected with said platen shifting means for variably shifting certain of said devices when said platen is shifted.
21. In a typewriting machine, the combination of a platen, platen shifting means, a ribbon vibrator having a single normal position, actuating devices therefor including a link, means including a member for normally changing the position of said link, and connections between said member and said platen shifting means for variably moving said link when the platen is shifted.
22. In a typewriting machine, the combination of a platen, platen shifting means, a ribbon vibrator, actuating devices therefor including a link and a lever, means for changing the relationship between said link and said lever to vary the throw of said vibrator, and means connected with said platen shifting means for relatively shifting said link and said lever variable extents.
23. In a typewriting machine, the combination of a platen, platen shifting means, a ribbon vibrator, actuating devices therefor including a link and a lever, means for changing the relationship between said link and said lever, and means connected with said platen shifting means for relatively shifting said link and said lever variable extents, the amount of relative shift depending on the relationship between said link and said lever at the time said shift occurs.
24. In a typewriting machine, the combination of a platen, platen shifting means, a ribbon vibrator, actuating devices therefor including a link and a lever, automatically acting means for changing step-by-step the relationship between said link and said lever, and means operative by said platen shifting means for relatively shifting said link and said lever, the amount of such relative shifting being variable and depending on the relationship between said link and said lever at the time the shift takes place.
25. In a typewriting machine, the combination of a platen, platen shifting means, a ribbon vibrator, an operating lever therefor, a key operated actuating link connected to said lever, means operative on said link to change its relationship with said lever, and means operative by said platen shifting means for shifting said link relatively to said lever, the extent of shifting movement of said link varying according to the relationship between the link and the lever at the time the shift takes place.
26. In a typewriting machine, the combination of a platen, platen shifting means, a ribbon vibrator, an operating lever therefor, a key operated actuating link connected to said lever, hand controlled means for setting said link in any one of a plurality of predetermined relationships with said lever, and means connected with said platen shifting means for variably shifting said link relatively to said lever.
27. In a typewriting machine, the combination of a platen, platen shifting means, a ribbon vibrator, an operating lever therefor, a key operated actuating link connected to said lever, hand controlled means for setting said link in any one of a plurality of predetermined relationships with said lever, and means connected with said platen shifting means for variably shifting said link relatively to said lever, the extent of the shifting movement of said link varying with the predetermined relationship between said link and said lever at the time the shift takes place.
28. In a typewriting machine, the combination of a platen, a ribbon vibrator, actuating devices therefor, a ribbon driving shaft, and means operative by said driving shaft for changing the relationship between certain of said actuating devices, said means including an eccentric, a frame movable by said eccentric, and a cam member controlled by said frame.
29. In a typewriting machine, the combination of a platen, a ribbon vibrator, actuating devices therefor, ribbon feeding mechanism for feeding the ribbon longitudinally including a driving shaft, and means operative by said driving shaft for changing the relationship between certain of said actuating devices, said means including an eccentric, a frame progressively movable back and forth by said eccentric, and a cam member progressively movable by said frame.
30. In a typewriting machine, the combination of a platen, shifting means for the platen, a ribbon vibrator, actuating devices therefor, ribbon feeding mechanism for

- feeding the ribbon longitudinally including a driving shaft, and means operative by said driving shaft for changing the relationship between certain of said actuating devices, said means including an eccentric, a frame progressively movable back and forth by said eccentric, a cam member progressively movable by said frame, and a slideable connection between said cam member and said platen shifting means.
31. In a typewriting machine, the combination of a platen, a ribbon vibrator, actuating devices therefor including a link, a ribbon driving shaft, an eccentric connected therewith, a frame controllable by said eccentric, and a cam member operative on said link and connected with said frame.
32. In a typewriting machine, the combination of a platen, a ribbon vibrator, actuating devices therefor including a link, a ribbon driving shaft, an eccentric connected therewith, a frame controllable by said eccentric, a cam member operative on said link and connected with said frame, and manually operated means for rendering said eccentric inoperative and for setting said cam member.
33. In a typewriting machine, the combination of a platen, a ribbon vibrator, actuating devices therefor including a link, a ribbon driving shaft, an eccentric connected therewith, a frame controllable by said eccentric, a cam member operative on said link and connected with said frame, and manually operated means for rendering said eccentric inoperative and for setting said cam member, said means comprising a shift frame slideable relatively to said first named frame and also operative to move the latter.
34. In a typewriting machine, the combination of a platen, a ribbon vibrator, actuating devices therefor including a link, a ribbon driving shaft, an eccentric connected therewith, a frame controllable by said eccentric, a cam member operative on said

link and connected with said frame, and manually operated means for rendering said eccentric inoperative and for setting said cam member, said means comprising a shift frame slideable relatively to said first named frame and also operative to move the latter, said shift frame being provided with cam notches operative on said eccentric to move it out of said first named frame.

35. In a typewriting machine, the combination of a platen, a ribbon vibrator, actuating devices therefor including a link, a ribbon driving shaft, an eccentric connected therewith, a frame controllable by said eccentric, a cam member operative on said link and connected with said frame, a hand controlled shift frame for disconnecting said eccentric from said first named frame and for subsequently moving said first named frame to set said cam member in any one of a plurality of predetermined positions.

36. In a typewriting machine, the combination of a platen, platen shifting means, a ribbon vibrator, actuating devices therefor including a link, a ribbon driving shaft, an eccentric connected therewith, a frame controllable by said eccentric, a cam member operative on said link and connected with said frame, a hand controlled shift frame for disconnecting said eccentric from said first named frame and for subsequently moving said first named frame to set said cam member in any one of a plurality of predetermined positions, and constantly maintained connections between said cam member and said platen shifting means.

Signed at the borough of Manhattan, city of New York, in the county of New York, and State of New York, this 28th day of April, A. D. 1910.

STEFANUS NIELSEN.
